C. C. HANSEN

INDEPENDENT ROTATION FOR PERCUSSIVE TOOLS

Filed Apr. 7, 1922

UNITED STATES PATENT OFFICE.

CHARLES C. HANSEN, OF EASTON, PENNSYLVANIA, ASSIGNOR TO INGERSOLL-RAND COMPANY, OF JERSEY CITY, NEW JERSEY, A CORPORATION OF NEW JERSEY.

INDEPENDENT ROTATION FOR PERCUSSIVE TOOLS.

Application filed April 7, 1922. Serial No. 550,421.

To all whom it may concern:

Be it known that I, CHARLES C. HANSEN, a citizen of the United States, and a resident of Easton, county of Northampton, and 5 State of Pennsylvania, have invented a certain Independent Rotation for Percussive Tools, of which the following is a specification, accompanied by drawings.

This invention relates to fluid actuated

10 percussive tools, such as rock drills, which may be of the hammer type but relates more particularly to means independent of the piston for imparting rotation to the drill steel.

15 The objects of the invention are to simplify and reduce the cost of constructing and assembling the rotation motor on the drill cylinder, enable the motor to be conveniently and readily mounted at the back 20 end of the cylinder, and produce a construction by means of which the motor may be secured and supported at the side of the cylinder, by means of longitudinal bolts.

Further objects of the invention will hereinafter appear and the invention is shown in one of its preferred forms in the accompanying drawings, in which,

25 Figure 1 is a side elevation partly broken away and partly in longitudinal section of 30 so much of a rock drill as will serve to illustrate the invention.

Figure 2 is a horizontal sectional plan view on the line 2—2 of Figure 1, and

35 Figure 3 is a detail transverse sectional view of the motor on the line 3—3 of Figure 2 looking in the direction of the arrows.

Referring to the drawings, the cylinder A is provided with a fluid actuated reciprocating hammer piston B of any suitable type, and the drill steel C extends into the front head D in position to receive the impact blows of the piston. Motive fluid for operating the piston is supplied to the machine 40 at the inlet E controlled by the throttle valve F in the back head G and the cylinder A, front head D and back head G are held together by the usual side bolts H.

50 Rotation is imparted to the drill steel C by means of a rotation motor, in this instance shown as a rotary gear motor, having the gears J and K suitably mounted in a motor casing L, which is adapted to be removably mounted at the side of the rear-

ward end of the cylinder A and one of the 55 gears, as the gear K is operatively connected to rotate the drill steel through suitable driving connections.

In accordance with this invention, the cylinder is formed with a reduced extension 60 O and a projection forming a shoulder P at the rearward end of the cylinder, located forwardly of the back end Q of the cylinder extension and formed with a plane face.

The motor casing L, as shown, is open at 65 the front end and preferably provided with an integral back head R, although the back head could be a separate plate if desired. The open end of the motor casing L is adapted 70 to be secured against the plane face or surface of the projection P on the cylinder, which thereby forms one head of the motor casing. The motor casing is thus located adjacent or in proximity to the cylinder extension O, and in accordance with my construction, the motor casing does not bear 75 upon the cylinder extension, but a space S is left between the bottom of the motor casing and the cylinder extension, which permits the motor to exhaust through the ex- 80 haust openings T into the space S beneath the motor, and from thence to atmosphere through the space or passage S', between the back head G and the motor casing. Fluid pressure is supplied to the motor cas- 85 ing through the admission port U from a port V in the back head G communicating with the supply controlled by the throttle valve F.

The construction described avoids the ne- 90 cessity of machining the surface of the cylinder extension O beneath the motor, and requires only that the plane surface or face of the cylinder projection P be machined to form a tight fit with the motor casing. The 95 motor casing is readily secured and centered upon the cylinder projection P as by means of longitudinal bolts W passing through the motor casing and the cylinder projection, and by this means the bolts are better 100 able to resist longitudinal strains.

The cylinder back head G is suitably centered over the back end of the cylinder extension O in any suitable manner, in this instance the back head G being provided with 105 the flange X, only a portion of which is shown for illustrative purposes. The back head G forms a back head for the cylinder and also

extends outwardly over the motor casing, and a suitable packing Y may be provided between the back head G and the motor casing, to connect the port V in the back head 5 with the port or passage U in the motor casing.

The gears J and K are preferably interchangeable and each provided with key-ways a , so that either gear or any gear of this 10 construction, may be keyed to the section b of the driving shaft, as by means of a key c . The gear J rotates on roller bearings d on the stationary shaft e having bearings in the motor casing, and cylinder projection 15 respectively. The driving shaft is preferably formed in sections b and f suitably coupled together as by means of the undercut and overlapping portions g and h , and a loose sleeve j is placed over the shaft and 20 extends over the coupling members within the chamber k , in the cylinder A through which the shaft extends. The shaft section b rotates in a roller-bearing o in the back head R of the motor casing, and in a roller-bearing p carried in the bushing q in the 25 body portion of the cylinder. Shaft section f rotates in the roller-bearing r carried in the bushing s at the forward end of the cylinder body. Slight clearance is provided 30 between the ends of the shaft sleeve j and the roller-bearing bushings q and s so that when the motor casing and motor gears are removed from the machine, thus separating the shaft section b from the shaft section f , 35 but leaving the roller-bearing p in position, the shaft sleeve j may be utilized to push the roller-bearing p from the bushing q . Obviously, after the front head D of the 40 machine has been removed, and the parts connected therewith, including the roller-bearing r , a tool may be inserted against the shaft sleeve j to push the sleeve longitudinally. Suitable gear connections are provided for transmitting rotation from the 45 driving shaft of the motor to the drill steel, and for this purpose, the shaft section f is provided with a pinion t meshing with a gear u having a pinion v meshing with a gear w , which is suitably secured as by 50 means of screw threads x , to the chuck y for rotating the chuck. A chuck sleeve z is preferably inserted within the back end of the chuck, and the chuck bushing 2 is inserted in the chuck against the chuck sleeve z . 55 The chuck y is suitably clutched to the chuck key 3 , and rotation is imparted to the drill steel through the agency of the usual lugs 4 on the shank of the steel, which engage the chuck y . Within the front end of the cylinder is preferably located the front cylinder bushing 5 through which the forward extension 6 of the piston B reciprocates, and in order to provide air for blowing down through the drill steel, the piston extension 60 6 is preferably formed with several grooved

or flattened portions 7 , so that air may blow through said grooves or flattened portions from the cylinder when said grooves enter the cylinder as the piston moves to the end of its rearward stroke.

70

I claim:

1. A fluid actuated percussive tool having a cylinder and a piston adapted to operate therein, and a motor operatively connected to rotate the drill steel, said cylinder having a projection at its rearward end formed with a plane face, said motor having a casing open at the front end and adapted to be removably secured against the face of said projection which thereby forms one head of the motor casing, longitudinal bolts for securing the motor casing against the face of said projection, a back head for the cylinder extending outwardly over the motor casing, and means for clamping the back head to the cylinder.

75

2. A fluid actuated percussive tool having a cylinder and a piston adapted to operate therein, and a motor operatively connected to rotate the drill steel, said cylinder having a reduced rearward extension and a projection forwardly of the back end of said extension formed with a plane face, said motor having a casing open at the front end and adapted to be removably secured adjacent the cylinder extension and against the face of said projection which thereby forms one head of the motor casing, longitudinal bolts for securing the motor casing against the face of said projection, a back head for the cylinder extending outwardly over the motor casing, and means for clamping the back head to the cylinder.

80

3. A fluid actuated percussive tool having a cylinder and a piston adapted to operate therein, and a motor operatively connected to rotate the drill steel, said cylinder having a reduced rearward extension and a projection forwardly of the back end of said extension formed with a plane face, said motor having a casing open at the front end and adapted to be removably secured against the face of said projection without bearing upon the cylinder extension, the projection forming one head of the motor casing, longitudinal bolts for securing and supporting the motor casing in position against the face of said projection, a back head for the cylinder extending outwardly over the motor casing, and means for clamping the back head to the cylinder.

100

4. A fluid actuated percussive tool having a cylinder and a piston adapted to operate therein, and a motor operatively connected to rotate the drill steel, said cylinder having a reduced rearward extension and a projection forwardly of the back end of said extension formed with a plane face, said motor having a casing open at the front end and adapted to be removably secured against the

110

115

125

130

face of said projection without bearing upon the cylinder extension, the projection forming one head of the motor casing, exhaust apertures in the motor casing leading to the space between the motor casing and the cylinder extension, longitudinal bolts for securing and supporting the motor casing in

position against the face of said projection, a back head for the cylinder extending outwardly over the motor casing, and means for 10 clamping the back head to the cylinder.

In testimony whereof I have signed this specification.

CHARLES C. HANSEN.
